UNITED STATES PATENT OFFICE

SAMUEL J. JOHNSON, OF CINCINNATI, OHIO, ASSIGNOR TO THE SEINSHEIMER PAPER COMPANY, OF CINCINNATI, OHIO, A CORPORATION OF OHIO

GARMENT-HANGER COVER

Application filed August 13, 1928. Serial No. 299,168.

This invention relates to improvements in pliable paper coverings or envelopes for commercial garment hangers and is particularly directed to an improvement incorporated in 5 the type of covering or envelope disclosed in my co-pending application, Serial No. 239,227, filed December 10, 1927, for garment hanger cover.

The garment hanger now in commercial 10 use, and to which the present improvement has especial applicability, is formed of a length of wire, the wire being bent into a triangle, the upwardly disposed ends thereof intertwined and one end terminating in a 15 hook.

It is an object of this invention to provide an inexpensive pliable paper envelope for a hanger which incorporates a means for locking or maintaining the envelope in position 20 relative to the hanger, this means cooperating with the formation of the hanger at the apex thereof. This type of covering or protector is designed to eliminate the use of pins or other sharp fastening devices for holding 25 the covering in place which might be injurious to delicate garments supported on the hanger. It furthermore achieves the object of providing an inexpensive covering for a hanger which is quickly applied thereto and 30 located in locked position by a means formed integral with the envelope.

Other objects and further advantages will be more fully set forth in a description of the accompanying drawings forming a part of 35 this specification, in which:

Figure 1 is a front view of the envelope showing it in locked position on a hanger, the hanger being illustrated in dot and dash lines.

Figure 2 is a view of the reverse or rear side 40 of the covering shown in Figure 1, showing the locking tab or flap folded against the rear side of the envelope.

Figure 3 is a fragmentary detailed view of the apex portion of the envelope showing it 45 apart from the hanger and as furnished to the user.

Figure 4 is a sectional view taken on line 4—4, Figure 1, detailing the folding of the flap.

50 Referring to the drawings, the commercial

type of wire hanger is indicated at 1. The covering or envelope is indicated at 2 and shown disposed on the hanger. The hanger is woven from a single strand of wire and forms a triangle, the wire portions 3 at the 55 apex portion being flat for a short distance before being turned upwardly at right angles and intertwined.

One of the intertwined ends of the strand of wire is of a greater length and is bent to 60 form the attaching hook 4 for the hanger. The protecting envelope or covering is substantially of the same shape and contour as the hanger, completely enclosing or enwrapping the hanger but leaving exposed the 65 straight apex portions 3 and the extending hook.

The envelope as heretofore disclosed is formed of a single sheet of material folded upon itself and joined by overlapping and adhesively securing the adjacent ends along a 70 seam 9 at the rear side centrally of the envelope.

The particular pattern formation and folding provides an open base 5 for the covering 75 and an orifice 6 through the apex thereof so that the hanger may be inserted bodily through the lower end of the envelope and the hanger hook forced through the orifice in the apex, the orifice being of a dimension to permit the passage of the hook therethrough.

A locking tab or flap 7 is formed by continuing upward the front wall 10 of the hanger. The tab is of the same width as the orifice and the edges 8 of the orifice formed 85 by the rear wall sections of the envelope are substantially straight cut. The tab may be of any suitable height to permit its manipulation and to render it efficient in a manner hereinafter described.

The straight portion of the hanger or the portion of the strand of wire adjacent the intertwined ends thereof is disposed slightly above the rear edges of the orifice of the covering, and the flap prior to tucking and folding 95 lies flat against the face of the shank or intertwined portions of the hanger.

As shown in Figures 1 and 2 the flap is tucked under the straight apex portion 3 of the hanger and folded down against the rear 100

side of the covering. This enwraps the envelope tightly at the apex point and prevents any accidental dislodging of the envelope from its position or any lateral shifting relative to the hanger hook shank which would result due to the large hook clearance opening 6.

Having described my invention, I claim:

1. A pliable covering for commercial clothes hangers, comprising, a flat triangular shaped envelope of supple texture paper material having a full width open lower end adapting the envelope to be slipped over the hanger and open at the apex for the projection of the hanger hook therethrough, and a lock flap formed integral with a side of the envelope adjacent the opening at the apex, said flap extending upwardly from the margin of the opening and folded on the line of joinder of the flap with the body of the envelope and against the face of the envelope and thereby adapted to be slipped under the hanger hook portion.
2. A pliable covering for commercial clothes hangers, comprising, a flat triangular shaped envelope of paper material having an open lower end adapting the envelope to be slipped over the hanger and open at the apex for the projection of the hanger hook therethrough, and a tab formed on the envelope adjacent the opening at the apex, said tab folded on a line coincidental with the line of the apex of the envelope and insertable under the hanger bar portion which extends across the opening in the envelope for locking the envelope on the hanger.
3. A pliable covering for commercial clothes hangers, comprising, a flat triangular shaped envelope of paper material having an opening in the apex thereof for the projection of the hanger hook therethrough, and a locking flap formed on the envelope extending upwardly from one face thereof adjacent the opening, said flap adapted to be tucked into position beneath the hook portion of the hanger for locking the envelope on the hanger.

In witness whereof, I hereunto subscribe my name.

50 SAMUEL J. JOHNSON.
